UNITED STATES PATENT OFFICE.

WILLIAM C. SANFORD, OF GOLCONDA, ARIZONA.

PLAYING-CARD GAME.

1,159,105.

Specification of Letters Patent.

Patented Nov. 2, 1915.

Application filed July 26, 1915. Serial No. 41,921.

To all whom it may concern:

Be it known that I, WILLIAM C. SANFORD, a citizen of the United States, residing at Golconda, in the county of Mohave, State of 5 Arizona, have invented certain new and useful Improvements in Playing-Card Games, of which the following is a description, reference being had to the accompanying drawings, forming a part hereof.

10 My invention relates to playing card games and consists in a game of "Election" to be played with cards representing the different States of the United States and their respective electoral votes, and other cards 15 representing certain interests; to be played in the manner hereinafter described.

Referring to the drawings:—Figure 1 represents a series of playing cards embodying my invention, each card shown being a 20 specimen card of a different suit. Fig. 2 represents tabulated statements of the cards of each suit, with their taking values and counting values.

The game is played with a pack composed 25 of sixty cards, which is made up of twelve cards each of five different suits. The suits are as follows: eastern suit, southern suit, central suit, western suit, and interest suit. In Fig. 1 there is shown one card of each 30 suit; 1 indicating a specimen card of the eastern suit, 2 a card of the southern suit, 3 a card of the central suit, 4 a card of the western suit, and 5 a card of the interest suit. Each card of the first four suits bears 35 the name of a State, a letter in the upper left corner indicating the suit, a number in the upper right corner indicating the order or taking value in the suit, and a number near the center indicating the counting 40 value or number of electoral votes. Each card of the interest suit bears the name of an interest, a letter in the upper left corner indicating the suit, and a number in the upper right corner indicating the order or taking 45 value in the suit. These indications, as is usual in playing cards, are preferably printed in duplicate so as to read downward from either end of the card. The cards in each of the State suits are ranked in order of taking 50 value, as indicated by their electoral votes;

and where two or more States of a suit have the same number of electoral votes, they may be placed in order of population. In determining the electoral votes, the apportionment act of 1911 is followed, but it is to 55 be understood that the order may be revised as changes are made in apportionment. The order of the cards of the interest suit is arbitrary, it being necessary only for the purpose of the game that there be twelve interest cards and that they have a relative 60 taking value from 1 to 12.

The cards may, if desired, be provided with designs such as representations of the seals of the several States, outline maps, or 65 any distinctive matter which would add to the attractive appearance of the card, or to the useful information carried by it.

The game is played by four players. The dealer and the player seated opposite him 70 are partners; the two other players are also partners, and are adversaries of the dealer. The cards are all dealt around to the left, one at a time. The interest suit is always the trump suit, but the cards of this suit 75 have no counting value. The player at the dealer's left leads. It is obligatory to follow suit, if possible. When holding none of the suit led, a player may trump the trick or play a card of any other suit. The highest 80 trump played, or if no trumps are played, the highest card in taking value of the suit led, wins the trick. The winner leads for the next trick. After a hand has been played, the votes are counted; and the side 85 having taken a majority of the electoral votes shall score the number of their majority as points for game. The game may be any convenient number of points.

It is a game of great interest, combining 90 chance and skill in pleasing proportions. It is of high educational value, tending to impart information regarding political and geographical conditions, and to stimulate interest in national politics. It is easily 95 learned, especially by any one familiar with ordinary card games; but with new and interesting features, such as suits of different counting value, and non-changing, non-counting trump suit.

Having thus described my invention, what I claim is:—

A game device comprising a pack of cards arranged in five suits: the cards of four of the suits each bearing the name of a State, designating marks indicating the suit to which it belongs, the electoral vote of the State, and its taking value relative to the

other cards of the suit; the cards of the fifth suit each bearing the name of an interest, 10 designating marks indicating the suit to which it belongs, and its taking value relative to the other cards of the suit.

This specification signed this nineteenth day of July A. D. 1915.

WILLIAM C. SANFORD.
